SPRAY DEVICE

William E. Pearl, Brooklyn, N. Y.

Application September 24, 1932
Serial No. 634,686

12 Claims. (Cl. 299—84)

This invention relates to spray devices such as shower heads, and the like articles.

An object of this invention is to provide a device of the character described having incorporated into the shower head a container adapted to be filled with bath salts or the like soluble material, and means for directing the water either to the container or to a chamber in the shower head separate from the container. Thus, for example, the container with the salts may be placed within the shower head and the user may start the shower by diverting the water from the container until the water reaches a proper temperature. By a simple manipulation which may be made by the user without moving from beneath the shower head, the water may be directed to pass to the container for impregnating the same with the salts.

A further object of this invention is to provide in a device of the character described, highly improved means for removing and replacing the container for the salts, whereby said container may be readily refilled.

A still further object of this invention is to provide a compact and rugged device of the character described which shall be comparatively inexpensive to manufacture, comprise few and simple parts, which shall be easy to manipulate and yet practical and efficient to a high degree in use.

Other objects of this invention will in part be obvious and in part hereinafter pointed out.

The invention accordingly consists in the features of construction, combination of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an elevational, axial, sectional view of a shower head embodying the invention;

Fig. 2 is a partial view similar to Fig. 1 but showing the valve in another position;

Fig. 3 is a cross-sectional view taken on line 3—3 of Fig. 1;

Fig. 4 is a cross-sectional view taken on line 4—4 of Fig. 1;

Fig. 5 is a fragmentary perspective separated view of a detail;

Fig. 6 is an elevational, axial, sectional view of a shower head embodying the invention, but illustrating a modified construction; and

Fig. 7 is a cross-sectional view taken on line 7—7 of Fig. 6.

Referring now in detail to the drawing, and particularly to Figs. 1, 2, 3 and 4 thereof, 10 designates a spray apparatus, here shown in 60 the form of a shower head comprising a substantially bell shaped member 11 which may be made as a single casting or in any other suitable manner. The member 11 is formed with a tubular neck portion 12 internally screw threaded 65 as at 12a whereby the device may be screwed to any suitable water supply pipe. Extending from the tubular portion 12 is an enlarged portion 13 having a flat bottom surface 13a and formed with a preferably somewhat tapering bore 15 disposed 70 transversely of said tubular portion and open at one end 16 thereof and closed by an end wall 17 at the opposite end thereof. The open end portion 16 is formed with an internally screw threaded 75 portion 18 for the purpose hereinafter appearing.

Said enlarged portion 13 is further formed on opposite sides of bore 15, with aligned, vertical openings 19 and 20 of preferably substantially elliptical cross-section and coaxial with the tubular portion 12. Extending from said enlarged portion 13 of member 11, is an outwardly and downwardly flaring, ornamentally shaped, portion 22, terminating in an inwardly beaded annular rim 23. Extending from the undersurface 85 13a of said enlarged portion 13 is a downwardly extending cylindrical portion 25 coaxial with respect to tubular portion 12, and terminating at 26 at substantially the level of the rim 23. A flat annular plate or ring 30 having a plurality 90 of pin holes or perforations 31 may be attached at the inner and outer edges thereof to the rim 23 and the lower end 26 of said cylindrical or tubular wall 25, by soldering or in any other suitable manner. A chamber 27 is thus formed 95 between the tubular wall 25 and the flaring wall 26. A passage or opening 29 formed in the enlarged portion 13, interconnects the chamber 27 with the bore 15 for the purpose hereinafter appearing.

The upper end portion of the inner surface of said cylindrical wall 25 may be formed with internal screw threads 34, and received within said cylindrical wall is a tubular casing 35 having an externally screw threaded upper end portion 105 screwed to said screw threaded portion 34, as shown in Fig. 1 of the drawing. The casing 35 may be open at the upper end thereof and formed with a bottom wall 37 provided with pin holes or perforations 38 for the purpose herein. 110

after stated. Said casing 35 preferably extends below the plate 30 as illustrated in Fig. 1 of the drawing.

Disposed within said casing is a container 40 comprising a cylindrical wall 41 to the bottom end of which there is attached a circular wire mesh screen disc 42, or other foraminous sheet. The cylindrical wall 41 is provided with an outwardly turned bead 43 somewhat spaced below the upper open end thereof. Mounted on the upper end of the tubular member 41 is a cap 45 having a cylindrical flange 46 frictionally receiving said upper end and contacting said bead 43, and a horizontal wall 47 formed with a plurality of spaced openings 49. Pivotally attached to said disc 47, as for example, by means of a central rivet 50, is a disc 51 formed with openings 52 adapted to register with openings 49. The disc 51 may be provided with an upturned flange 53 which may be grasped by the hand to turn said disc whereby the openings 52 and 49 may be more or less overlapped or adjusted.

Means is provided for directing water from the tubular member 12 either to the passage 29 and chamber 27 or to the tubular receptacle or casing 35 for dissolving bath salts or the like soluble material in the container 40. To this end there is rotatably mounted within the bore 15, a tapered cock or valve member 60 having a transverse through passage or opening 61 adapted to register with the openings 19 and 20 in the position shown in Fig. 1 of the drawing. Said bore is further provided with a passage 63 disposed transversely of and communicating with the passage 61, whereby upon rotating the valve in a clockwise direction, from the position shown in Fig. 1 to the position shown in Fig. 2, the opening 63 will register with the opening 19, and one end of the passage 61 will register with the passage 29 thus cutting off the supply of water from the casing 35 and passing the water to the chamber 27.

Means is provided for manipulating the valve from beneath the shower. To this end, said valve 60 is provided with an axial pin 65 of reduced diameter projecting from the open end of the bore 15. A ring or nut 66 received over said pin 65 may be screwed to the threaded opening 18 for retaining the valve within said bore 15. Interposed between the valve 60 and the nut 66 is a washer 67 for properly positioning said valve within said bore. Said valve may further be provided with a reduced projection 68 contacting the inner surface of the end wall 17. Received over the outer end of the pin or shaft 65 is a sleeve 69 fixed thereto in any suitable manner. Attached to the outer end of said sleeve 69 is a bar or handle 71 preferably disposed adjacent the shower head and projecting downwardly at a 45° angle in the position shown in Fig. 1 thereof. To move said handle to the position shown in Fig. 2, the same need merely be swung 90° to bring the same to an opposite 45° inclination.

For limiting rotation of the valve to the positions shown in Figs. 1 and 2, the screw 66, as illustrated in detail in Fig. 7 of the drawing, is provided with an annular lug or projection 73 forming an annular cut out portion 74. The sleeve 69 is provided with a lug or projection 75 extending into the cut out portion 74. The lug 75 is of smaller angular extent than the cut out portion 74 so that rotation of said sleeve will cause the ends 76 of said lug 75 to contact the end portions 77 of the lug 73. As stated above, the lugs 73 and 75 are so proportioned as to permit the sleeve

a rotation of 90° whereby the handle may be moved from the position shown in Fig. 1 to the position shown in Fig. 2.

To refill the container 40, the user may remove the casing 35 by unscrewing the same, lift the cap 45 off the top of the container 40 and fill the latter with bath salts. The cap 45 may then be replaced and the upper disc 51 moved to adjust the amount of overlap of openings 49, 52 to the desired degree. The casing 35 may then be again inserted within the tubular member 25 and screwed to the upper end of the latter. The handle 71 may then be moved to the position shown in Fig. 2 of the drawing so that water will be directed to the passages 19, 63 and 61, to the passage 29 and the chamber 27. When the water has reached the proper temperature the user need merely raise his arm and swing the handle 71 to the position shown in Fig. 1 of the drawing. The water will then pass through the opening 20 to the casing 35. Water will of course, pass through the overlapping portion of the openings 52 and 49 to dissolve the salts in container 40, and the impregnated water will flow through the screen 42 and the pin holes or perforations 38.

In Figs. 5 and 6 of the drawing is shown a modified construction comprising a shower head 10a formed of a bell-shaped member 80 having an internally screw threaded neck portion 81 for attaching to a water supply pipe. Extending from the neck portion 81 is a hollow portion 82 formed with a lower internally screw threaded rim 83. Screwed to said portion 83 is a substantially frusto-conical shaped member 84 formed with a flat top wall 85 having external threads for engagement with the threads of the portion 83. The lower end of the portion 84 is likewise formed with an inwardly extending annular bead 88. Extending downwardly from the wall 85 is a cylindrical concentric wall 89, the lower end thereof terminating substantially at the level of said bead 88. A flat annular ring or plate 90 is attached at the inner and outer edges thereof to the lower end of said cylindrical member 89 and the bead 88. Said plate 90 may be formed with perforations 91 to permit water in the chamber 92 disposed about the cylindrical portion 89, to pass to the user. Said top wall 85 may further be formed with a pair of inner and outer concentric annular rows of spaced openings 93 and 94. Said top wall 85 may be further formed, for the purpose herein-after appearing, with a central opening 95. Rotatably mounted on said wall 85 is a plate 96 having a central tubular flange 97 rotatably disposed within the opening 95 and formed with internal screw threads.

Said plate 96 is likewise formed with a pair of inner and outer annular concentric rows of spaced openings 93a and 94a. In one position of the plate 96, the openings 93a register with the openings 93, and the openings 94a are unaligned with openings 94; and in another position of the plate, openings 94a register with the openings 94, and openings 93a are unaligned with openings 93. Disposed within cylindrical wall 89 and contacting the undersurface of wall 85 is a disc 100 having an externally screw threaded projection 101 engaging the threaded portion 98 of tubular projection 97. Said disc 100 is formed with an annular row of openings 103 aligned with the openings 93a of plate 96 when said disc is attached to said plate.

Said disc 100 may be further provided at the periphery thereof with a plurality of radially extending pins 104. A casing 105 formed with a

- cylindrical wall 106 may be detachably attached to the disc 100 by means of bayonet slots 107 formed in the upper ends of said cylindrical wall 106 and engaging said pins 104. The casing 105 is formed with a bottom wall 108 provided with perforations or pin holes 109 to permit water to pass therethrough. Mounted within said casing 105 on legs or brackets 110, is a cylindrical container 111 having a bottom wall 112 made of screen material 113; and mounted on the upper end of said container 111 is a cap 45a similar to the cap 45 shown in Fig. 1 of the drawing. The casing 105 may be readily detached from the disc 100 and the cap 45a removed to place salts within the container 111. Said cap may then be replaced and the casing 105 again attached to the underside of the disc 100 by means of the bayonet connection. The disc 100 being attached and movable with the plate 96, may be rotated therewith by means of casing 105. Said casing preferably projects below the plate 90 so that the lower end of the former may be grasped by the user for rotating said casing. By rotating the casing, the openings 93a and 103 may be moved out of registration with respect to the openings 93 to bring the openings 94 into registration with the openings 94a for directing water to the chamber 92. When the water is at proper temperature or when it is desired to impregnate the water with the salts within the receptacle 111, said casing 105 may be rotated to bring the openings 94a out of registration with respect to the openings 94, and the openings 93, and 103 into registration with respect to the openings 93. The water will then pass to the casing 105 for impregnating the salts within the container 111. Proper stops may be provided for limiting rotation of the casing 105 from the position wherein the water passes to the chamber 92 to the position wherein the water is diverted to said casing 105.
- It will thus be seen that there is provided a device in which the several objects of this invention are achieved, and which is well adapted to meet the conditions of practical use.
- As various possible embodiments might be made of the above invention, and as various changes might be made in the embodiments above set forth, it is to be understood that all matter herein set forth or shown in the accompanying drawing is to be interpreted as illustrative and not in a limiting sense.
- Having thus described my invention, I claim as new and desire to secure by Letters Patent:
1. A shower head comprising a member provided with a portion having a bore, and an outwardly flaring portion extending from said first portion, and a cylindrical wall portion extending from said first portion and disposed within said outwardly flaring portion, a flat annular perforated plate interconnecting the rim of said cylindrical wall with the rim of said outwardly flaring portion, to form a chamber therebetween, a casing received within said cylindrical wall and supported by said member, said casing having an exposed perforated wall portion, a container for bath salts or the like soluble material, disposed within said casing, and valve means within said bore and first portion for directing water selectively to said casing or chamber.
2. A shower head comprising a member provided with a water inlet and formed with a flat annular perforated wall having a central opening and a tubular wall extending from the inner periphery of said annular wall and a wall extending from the outer periphery of said annular wall forming a chamber with said tubular member, a casing extending into said tubular member and detachably attached to said member, said casing being formed with a perforated wall parallel to said flat annular wall, a container for salts within said casing, and valve means on said member for selectively directing water from said inlet to said chamber or casing.
3. A shower head comprising a member having a top portion and provided with an inlet, an outwardly flaring portion extending from said top portion and terminating in an annular bottom rim, a tubular wall within said outwardly flaring portion, extending from said top portion, and a flat annular plate interconnecting the outer rim of said tubular wall with the rim of said flaring wall and forming a chamber therebetween, said plate being formed with perforations, a casing received within said tubular wall and attached to said member, said casing being formed with a perforated wall portion, means within said casing for receiving bath salts or the like water soluble material, and means on said member for selectively directing water from said inlet to said chamber or casing.
4. A shower head comprising a member having a top portion provided with an inlet, an outwardly flaring portion extending from said top portion and terminating in an annular bottom rim, a tubular wall within said outwardly flaring portion, extending from said top portion, and a flat annular plate interconnecting the outer rim of said tubular wall with the rim of said flaring wall and forming a chamber therebetween, said plate being formed with perforations, a casing received within said tubular wall and attached to said member, said casing projecting beyond said plate and being formed with a perforated wall portion, means within said casing for receiving bath salts or the like water soluble material, and valve means on said member for selectively directing water from said inlet to said chamber or casing.
5. A shower head comprising a member having a top portion provided with an inlet, an outwardly flaring portion extending from said top portion and terminating in an annular bottom rim, a tubular wall within said outwardly flaring portion, extending from said top portion, and a flat annular plate interconnecting the outer rim of said tubular wall with the rim of said flaring wall and forming a chamber therebetween, said plate being formed with perforations, a casing received within said tubular wall and supported by said member, said casing being formed with a perforated wall portion parallel to said annular plate, means within said casing for receiving bath salts or the like water soluble material, and means for directing water selectively to said chamber or casing.
6. A shower head comprising a member having a tubular neck portion, an enlarged portion extending from said neck portion, an outer annular wall extending from said enlarged portion, a central cylindrical wall extending from said enlarged portion and disposed within said outer annular wall, a thin perforated plate interconnecting the outer ends of said cylindrical wall and outer annular wall, and formed with perforations, a casing for bath salts and the like water soluble substance slidably received within said cylindrical wall, said casing having an exposed perforated wall, and means for detachably attaching said casing to said member, and means for selectively directing water from said inlet to said chamber or casing.

directing water from said neck portion to said chamber or casing.

7. A shower head comprising a member having a tubular neck portion, an enlarged portion extending from said neck portion, an outer annular wall extending from said enlarged portion, a central cylindrical wall extending from said enlarged portion and disposed within said outer annular wall, a thin plate interconnecting the outer ends 10 of said cylindrical wall and outer annular wall, and formed with perforations, and a casing for bath salts and the like water soluble substance slidably received within said cylindrical wall, and means for detachably attaching said casing to 15 said member, said casing projecting beyond said plate and being formed with an end wall provided with perforations, and valve means for selectively directing water from said neck to said chamber or casing.

20 8. A shower head comprising a member having a tubular neck portion, an enlarged portion extending from said neck portion, an outer annular wall extending from said enlarged portion, a central cylindrical wall extending from said enlarged portion and disposed within said outer annular wall, a thin plate interconnecting the outer ends of said cylindrical wall and outer annular wall, and formed with perforations, a casing for 25 bath salts and the like water soluble substance slidably received within said cylindrical wall, means for detachably attaching said casing to 30 said member, said casing projecting beyond said plate and being formed with an end wall provided with perforations, and valve means for selectively 35 interconnecting said neck portion with said chamber or casing.

9. A shower head comprising a member having a tubular neck portion, an enlarged portion extending from said neck portion, an outer annular wall extending from said enlarged portion, a central cylindrical wall extending from said enlarged portion and disposed within said outer annular wall, a thin plate interconnecting the outer ends of said cylindrical wall and outer 45 annular wall and forming a chamber between said walls, and formed with perforations, a casing for bath salts and the like water soluble substance slidably received within said cylindrical wall, said casing having an exposed perforated portion, means for detachably attaching said 50 casing to said member, said enlarged portion being provided with a bore transverse to said neck portion and with aligned passages interconnecting said bore with the interior of said neck portion and with the interior of said casing, said enlarged portion being further formed with 55 a passage interconnecting said chamber with said bore, and a rotary valve member within said bore having a passage interconnecting said aligned 60 passages in one position thereof, said valve having a second passage communicating with the first passage thereof and interconnecting the same with the neck in another position thereof, said second passage of said valve communicating 65 with the passage which connects the bore with said chamber in said latter position.

10. A shower head comprising a member provided with an inlet and having a tubular opening, a casing received within said opening and

having an exposed perforated wall, means for detachably attaching said casing to said member, a tubular container mounted within said casing and having a screen at one end thereof and being open at the other end thereof, and a cap frictionally received on said other end of said container, said cap comprising a pair of discs pivoted to one another by a central rivet and having openings adapted to overlap upon causing relative rotation between said discs, and valve means for directing water from said inlet to said casing.

11. A shower head comprising a member having a neck portion and an enlarged hollow portion open at the bottom end thereof, a substantially frusto-conical member having a top wall screwed to the rim of said hollow enlarged portion, said second member further comprising a central cylindrical wall extending from said top wall and an outwardly flaring wall extending from said top wall, a plate interconnecting the outer rim edges of said cylindrical wall and the flaring wall and forming a chamber therebetween, said plate being perforated, said top wall being formed with a central opening, a plate rotatably mounted on said top wall and having a tubular projection rotatably received within said opening, a disc underlying said top wall and disposed within said cylindrical wall, said disc being screwed to said tubular projection, a casing received within said cylindrical wall, detachably attached to said disc and having a perforated wall parallel to said perforated plate, said top wall being formed with inner and outer openings discharging within and without said cylindrical wall respectively, said rotary plate being provided with inner and outer openings, the inner opening of said rotary plate being adapted to register with the inner opening of said top wall in one position of said rotary plate, and said outer opening of said rotary plate being adapted to register with the outer opening of said top wall in another position of said rotary plate, and said disc being provided with an opening aligned with the inner opening of said rotary plate.

12. A shower head comprising a member having a neck portion, a transverse wall portion connected to said neck to form a chamber therewith, a cylindrical wall extending from said transverse wall portion, an outer annular wall 125 extending from said transverse wall portion, a thin perforated plate interconnecting the outer ends of said cylindrical wall and outer wall, a plate rotatably mounted on said transverse wall portion, a casing received within said cylindrical wall and supported by said rotatable plate and having a perforated wall parallel to said thin perforated plate, said transverse wall portion being formed with a pair of openings discharging within and without said cylindrical wall, respectively and said second plate being formed with a pair of openings one of which is adapted to register with one of the openings of the transverse wall portion in one position of said rotatable plate, and the other of which is adapted to register with the other opening in said transverse wall portion in another position of said rotatable plate.

WILLIAM E. PEARL.
